UNITED STATES PATENT OFFICE.

JACOB SARDO, OF JOHNSTOWN, PENNSYLVANIA.

HAND-BOMB.

1,284,150.

Specification of Letters Patent.

Patented Nov. 5, 1918.

Application filed June 27, 1918. Serial No. 242,231.

To all whom it may concern:

Be it known that I, JACOB SARDO, a citizen of the United States, residing at Johnstown, in the county of Cambria and State of Pennsylvania, have invented certain new and useful Improvements in Hand-Bombs, of which the following is a specification.

My invention relates to bombs designed to be thrown by hand.

10 The object is to provide a hand bomb or grenade which can be conveniently thrown a much greater distance than has heretofore been found practicable to attempt.

Another object is to provide a bomb which 15 can be thrown with uniform accuracy.

A further object is to provide a bomb so constructed that the time fuse (when a fuse is used) will not be caught between the bomb and the ground, and damaged or cut off as 20 the bomb strikes the ground.

Other objects will appear in the subjoined description.

The invention consists in certain novel features of combination and arrangement of 25 parts as will be hereinafter described and claimed, reference being had to the accompanying drawings; in which Figure 1 is a perspective view of one of my improved hand bombs. Fig. 2 is a side view of the 30 same with the flexible member omitted. Fig. 3 illustrates in an exaggerated way the movements and path of travel of a bomb apparently like mine in general principle, but with a different arrangement of parts from that 35 which I employ; and Fig. 4 is a view illustrating the movements and path of travel of my improved bomb when thrown at an object. Fig. 5 is a view of my improved hand bomb, the same consisting of a pointed 40 projectile.

In carrying out my invention, I employ an elongated bomb 1 provided on its outside with a mark 2 at the point of its center of gravity, and having an elongated flexible member 3 secured at one end around the bomb at the center of gravity of the bomb, and free at its other end where it is preferably provided with means for more securely holding the flexible member by the hand of 50 the operator.

My present invention applies to all kinds of elongated hand bombs regardless of what kind of explosives and missiles may be used inside them. There are many different 55 kinds of fillings for bombs, and sometimes the same ingredients are employed in dif-

ferent proportions, all of these changes being made according to the effect sought to be produced; and any of these differences are liable to change the point of the center of gravity in the respective bombs. Hence the center of gravity falls at different points in different shells, even when the shells themselves are exactly alike. For this reason the mark 2 is not placed on the shell of my bomb 60 till the point of the center of gravity of the filled bomb is known.

Having the mark 2 on the shell enables a comparatively inexperienced person to attach the flexible member 3 at the correct 70 point in every instance. In handling and shipping the shells, this flexible member sometimes gets slipped out of place on a shell but the mark 2 indicates that fact to the eye of any interested observer, so that 75 it can at once be put back in its proper place. Also, if through carelessness or otherwise, the flexible member is sometimes broken off, it can be quickly replaced by a new one at 80 exactly the right place, by even the most unskilled person if necessary. The force of what has just been said about the flexible member slipping, and the value of the mark 2, etc., all grows out of the fact that these 85 bombs are often handled in the greatest haste, under the most extreme stress and excitement, and by the most inexperienced and unskilled persons. They are also very commonly used under circumstances where even a few seconds delay might result in irreparable loss including the life of the operator. Hence the great importance which here attaches to a matter which under ordinary 90 circumstances would be only trivial.

It will seldom happen that the center of gravity of the bomb will be at its longitudinal center, for as a rule one end of the bomb will be heavier than the other. Sometimes the heavier end will be the inner end and sometimes the outer end; and this brings us 95 to a consideration of the great importance and advantage of having the flexible connection 3 engage the bomb at approximately its center of gravity rather than at its longitudinal center or at any other point in its longitudinal extent or at either of its ends; but before discussing this point let it be noted that the bombs may sometimes be fired by fuses (the most important of which are time fuses), and sometimes by other ordinary or preferred means. Sometimes they are arranged to be fired by the concussion of 100 105 110

the bomb when it strikes the ground or other object upon which it falls. And since the bombs are fired in different ways the bombs illustrated in the drawings are not shown as 5 provided with fuses; but it will be pointed out that my way of throwing them is the best, whether they be provided with fuses or not.

Attaching a flexible connection to a bomb 10 enables the one throwing it to give it a longer swing and therefore impart to it a greater initial momentum, according to the well known principle of the sling: but one would naturally think that the best place 15 to attach the flexible connection would be at one end of the bomb rather than at the point where applicant attaches it, just as in throwing a stick one naturally takes hold of one end of it rather than at its middle portion 20 or anywhere else, as he seems to know he can throw it better that way: and the thrower soon also learns that the stick goes better when he takes hold of the lighter end of it in preference to the heavier end. But every 25 country-bred boy knows the practical impossibility of throwing a stick in the ordinary way without its turning end over end as it goes, especially if he makes a long throw. But he soon learns to take advantage 30 of this inevitable tendency of a stick to turn as it goes when thrown at an object, and so a stick or club becomes his favorite missile for bringing down apples and chestnuts from the trees, because with its wide sweep 35 as it turns over and over it is apt to hit a limb and release therefrom the desired treasure.

The Australian bushman also knows how 40 to take advantage of this tendency of a thrown stick to turn, and so he has become an expert with his boomerang and makes it work in a magical way to perform apparent impossibilities. But while every country boy knows that for a short throw he can 45 throw the stick (due to the swing he gets on it) farther than he could throw a stone of the same weight, yet when he wants to make a long throw and bring down the chestnuts from the tops of the high trees, he has to 50 resort to stones: he can't throw the stick far enough: and he can't throw a small stick as far as he can a heavier one, though of two stones of the same weight as the two sticks he can throw the lighter one the farthest.

55 Now, it is altogether desirable that bombs should be elongated in shape rather than otherwise: one that is cylindrical is much to be preferred to one that is spherical; one reason of this among others, being that an 60 elongated bomb is much more conveniently and economically manufactured and handled than one that is round like a ball, or any other shape. But it is also greatly important that these hand bombs should be capable of 65 being thrown the greatest possible distance,

which at times will be as great an advantage as to have longer range guns than the other fellow. Hence the problem confronting us is to provide means by which the elongated or cylindrical bomb may be thrown, if possible, as far as can one that is round like a ball. This at first sight may seem quite impossible, since, as has already been shown, a stick cannot be thrown as far as a stone. But the difficulty in throwing the stick does 70 not arise from the fact that it is elongated, but from the fact that its initial impulse is given it by swinging it unavoidably through a curve or the arc of a circle, of which the shoulder of the operator is, roughly speaking, the center, and this initial curve causes the stick to turn end over end and thus meet with great resistance from the atmosphere as it travels forward. The fact that one end of the stick is almost invariably heavier than 75 the other also somewhat increases the tendency of the stick to turn over as just above referred to, in addition to the fact that one end of the stick in its initial swing is swung through the arc of a greater circle than the 80 other end, and thus has more momentum imparted to it than the other end of the stick even if both ends should chance to be exactly alike. But while a stick is an elongated object, and one end is usually heavier than 85 the other, yet neither or both of these facts within themselves constitute the reason why a stick cannot be thrown farther than it can. This is abundantly proved by the fact that 90 an arrow which is usually greatly elongated, and heavier at one end than the other, can yet be shot to a great distance with a bow, and with great accuracy too. The shells shot from cannon are also elongated in preference to the round balls formerly 95 used: the long shell goes farther than the round ball. But no one can throw an arrow to any great distance by hand, for the reasons already set forth.

But notwithstanding the fact that any object that is thrown by hand sling fashion must unavoidably be thrown with an initial curve, applicant has discovered and set forth in this application a method by which an elongated object may be thrown with a 105 sling entailing the usual unavoidable curve, and yet without having imparted to the object thrown, in any considerable degree at least, that objectionable and hurtful tendency to turn end over end as fully referred to 110 above.

Fig. 3 of the drawings shows in an exaggerated way the movements and the path that would be traversed by a bomb thrown with a flexible member attached to the end 115 of the bomb. The end of the bomb farthest from the hand of the operator is here supposed to be slightly heavier than the other end to which the flexible connection is attached, and this heavier end is indicated 120

by a double line. Now this bomb is supposed to be thrown from the hand of the operator in the usual manner, *i. e.*, by a downward-and-upward swing. Let us notice in the first place that the flexible member or sling is of necessity comparatively short, since the bomb is of itself long enough to extend down from the hand of the operator to a point not very far from the ground 10 when the operator assumes the stooping position, as he must do to make the best possible throw. Then the flexible member must not be long enough to permit the bomb to strike the ground as it is swung. Hence 15 the flexible member will of necessity be too short to be very effective, since the power of a sling is in direct proportion to its length. In the next place a bomb thrown by a short sling, as indicated in this figure, 20 will have imparted to it a much greater tendency to turn end over end than if it had been thrown with a longer sling. The general direction of the forward movement of the bomb will of course be in a curved 25 line, but as the heavier end of the bomb goes up, as indicated by positions 5, 6, 7, 10, and 11, the whole bomb will tend to rise with it, and as the heavier end comes down, as indicated in positions 8, 9, 12, 13, and 14, 30 the whole bomb will tend in a measure to come down with it; so that the center of the bomb as it advances after having left the hand of the operator will travel in a wavy curve turning end over end as it goes, there- 35 by traveling in a long crooked path, and meeting with great resistance from the atmosphere. The result of all this will be that the bomb cannot be thrown very far or very accurately by a sling attached to one 40 of its ends as illustrated in Fig. 3.

If the sling should be attached to the heavier end of the bomb instead of the lighter end, the result would be still more unsatisfactory.

45 Moreover, if the slings are attached to the ends of the bombs, they will be in far greater danger of getting cut in two or worn off in handling and shipping, than if attached as shown in Fig. 1, and it would in 50 that case be hard to replace them. Again, if a time fuse is used in a bomb, the end of the bomb is the most convenient place for the fuse to enter the bomb; and if a bomb with a time fuse is thrown in the manner indicated in Fig. 3, when the bomb strikes the ground, the time fuse may get caught between the edge of the bomb and the ground and cut off.

I will now describe the operation of my 60 improved bomb as illustrated in Fig. 4. In the first place attention is called to the fact that the hand of the operator in Fig. 3 of the drawings is the same distance from the ground line 15, as is the hand in Fig. 4 from the ground line 16 of that figure. It be-

comes apparent at a glance that a much longer flexible member or sling 3 can be used with my device than with the other. That is one strong point in its favor, for the whole object of a sling is to get as long a 70 sweep as possible in throwing anything. In the next place, my bomb is thrown with its longitudinal axis disposed horizontally throughout its initial impulse, so that no tendency is imparted to the bomb to 75 move out of a horizontal position. Hence there will be no tendency in the bomb to turn end over end as it travels forwardly. As already stated, one end of every bomb is apt to be at least slightly heavier than 80 the other, and the resistance of the air will cause the heavier end of the bomb to move forward horizontally a little faster than the other end, and thus to gradually gain on the other end as the bomb advances toward 85 its goal, so that the bomb will presently be traveling in a longitudinal direction in much the same way as if it had been thrown from a mortar. It will travel in a true 90 curve and will have no tendency to travel in a wavy line or to turn end over end, as does the bomb illustrated in Fig. 3. For this reason the air resistance will be only slight as compared with that encountered 95 by a bomb thrown in the manner illustrated in Fig. 3.

The initial sidewise swing given the bomb will impart to it a slight tendency to rotate on its longitudinal axis, thus causing it to 100 slightly simulate the movements of a projectile shot from a rifled gun. This of course will be rather an advantage than otherwise to the bomb, tending as it does to increase the accuracy with which it will 105 travel toward its target.

My construction permits the longest possible flexible member or sling 3.

From the foregoing it will be seen that I have here produced a bomb arranged to be hurled to an unusual distance, in a manner 110 causing the bomb in its movements to simulate the movements of a projectile thrown from a rifled gun, so that with my arrangement bombs can be uniformly thrown with great accuracy at the desired targets.

Fig. 4 of the drawings clearly illustrates certain features referred to above. The bomb is here shown occupying its true horizontal position when given its initial impulse. As soon as it leaves the hand of the operator it begins to assume the position indicated at 17. A little farther on it has taken the position shown at 18, approaching nearer and nearer to a true longitudinal movement which is reached at 19. After this position 120 has been reached gravity will cause the heavier end of the bomb to begin to gradually point downwardly as indicated at 20 and 21. Therefore in the case of bombs that are not provided with fuses, but are designed to be 125 130

exploded by concussion, one may calculate with reasonable certainty that the heavier end of the bomb will strike the ground first, and arrange the firing means accordingly.

- 5 If the sling 3 be attached to the shell a shade in advance of the line 2 (which indicates the point of the center of gravity of the bomb), toward the heavier end of the bomb, this will cause the bomb to more readily 10 turn into the position indicated at 19 where it begins to advance in a longitudinal direction. On the other hand, if the sling 3 is attached to the shell a shade from the line 2 toward the lighter end of the shell, 15 the shell will be slower in reaching the position indicated at 19.

In Fig. 4 the line of travel of the bomb is indicated by the dotted curved line 22.

If the heavier end of the bomb be pointed 20 as illustrated in Fig. 5 of the drawings, instead of being flat, the resistance of the air encountered by the bomb in its flight will be still less.

It must not be inferred from the foregoing 25 that, when my bomb is given its initial swing, its longitudinal axis must be always disposed at exactly a right angle to the line of travel of the bomb, for if either end of the bomb be a little in advance of the other, 30 the heavier end will gradually gain on the lighter end till the longitudinal position indicated at 19 is reached. If the heavier end is in advance at the start the position referred to will be reached sooner, and if the

lighter end later, than when a true sidewise 35 swing is given. The law here referred to will always come into play unless the bomb is thrown end foremost, javelin fashion; and it can be thrown that way if desired, with the sling secured somewhat in advance of the 40 center of gravity in the direction of the forward end of the bomb.

Having now described my invention, what I claim as new and desire to secure by Letters Patent is:—

45 1. A hand bomb having an elongated shell provided with a flexible member for throwing the bomb, said flexible member engaging the shell at approximately the center of gravity of the bomb.

50 2. A hand bomb having an elongated shell; and a flexible connection engaging the shell around the outside thereof at approximately the center of gravity of the bomb, the shell being provided on its outside with a mark at the point of the center of gravity of the bomb.

55 3. An elongated hand bomb provided with a sling member for throwing the bomb, said sling member engaging the bomb between its ends at a material distance from either of said ends.

60 In testimony whereof I affix my signature.

JACOB SARDO.
